(Cl. D14—3)

To all whom it may concern:

Be it known that I, Ed B. Meripol, a citizen of the United States, residing in Los Angeles, in the county of Los Angeles, State of California, have invented a new, original, and ornamental Design for a Garden Tractor, of which the following is a specification, reference being had to the accompanying drawing, forming a part thereof.

the support shown at the right of Fig. 1 being omitted for convenience in illustration.

I claim:

The ornamental design for a garden tractor, substantially as shown and described.

ED B. MERIPOL.
